INVENTOR,

James L. Shannon,

BY

Harry W. Bowen,
ATTORNEY.

UNITED STATES PATENT OFFICE

JAMES L. SHANNON, OF SPRINGFIELD, MASSACHUSETTS, ASSIGNOR TO BLAKE MANUFACTURING COMPANY, A CORPORATION OF MASSACHUSETTS

ELECTRIC HAND FLASH LIGHT

Original application filed April 11, 1928, Serial No. 269,188. Divided and this application filed February 4, 1930. Serial No. 425,856

This invention relates to improvements in electric hand flashlights of the type shown, described and claimed in my prior Letters Patent of the United States of America, dated January 4, 1927, and Numbered 1,613,203, in which a plurality of electric light bulbs are employed with switch means for closing the circuits to any one of the bulbs or all of them simultaneously. The present application is a division of my pending application, Serial No. 269,188, filed April 11, 1928.

The present invention relates to the construction of the reflector end of the lamp in which a ring of insulation is inserted between the metallic head part of the lamp and the metallic reflector and means for removably retaining the same in place. The purpose of this ring of insulation is for insulating the metallic reflector from the metallic casing of the hand flashlight. Also, it is designed for centering the reflector when it is inserted in order that the contact terminals of each of the bulbs may engage the proper terminal or battery circuit wires when assembled. A spring ring is employed for retaining the ring of insulation in place but permitting it to be readily removed when the ring of insulation is to be removed.

Referring to the drawings:

Fig. 1 is an elevational view, partially in section, of the reflector end of the lamp with the lamp terminals and the ring of insulation retained in place by the spring wire ring.

Fig. 2 is a transverse sectional view on the line 2—2 of Fig. 1 showing the ring of insulation with the centrally disposed strip of metal extending across the ring and formed with an opening for receiving one of the terminals of the lamp.

Fig. 3 is a detail view of the ring of insulation removed from the lamp.

Fig. 4 is a sectional view on the line 4—4 of Fig. 3, showing the centrally disposed opening in the ring and the strip of metal attached to the ring.

Fig. 5 is a detail view of the wire spring for retaining the ring of insulation in place in the head portion of the lamp.

Referring to the drawings in detail:

1 designates the tubular cylindrical member of the lamp in which the battery, indicated by the dotted lines at 2, is placed. The terminal of the battery is indicated at 3 and engaged by the contact strip 3'. 4 is the enlarged head portion of the lamp which is formed with threads 5 for receiving the bezel or ring 6 that retains the lens 7 in place. The metallic parabolic reflector is indicated at 8 in which the three electric bulbs 9, 10 and 11 are mounted by means of the threaded sockets 12. 13 designates a flat ring of insulating material which is located within the metallic head member 4 as shown in Fig. 1. 14 designates a bead in which is located the wire spring 15 for retaining the flat ring of insulation 13 in place, yet permitting it to be readily removed, when desired. This ring of insulation serves to insulate the metallic reflector 8 from the metallic casing part 4. 16 is a strip of metal which is attached to the ring of insulation 13 by means of the rivets 17. This strip is formed with an opening 18 for receiving the threaded socket 12 of the lamp 10. The ring of insulation is formed with a centrally located opening 19 through which inner end of the reflector passes as shown. This opening is formed with the recesses 20, 21 and 22 for receiving the contact strips 23, 24 and 25. The contact strip 3' engages the terminal 3 of battery 2. The contact strips 24 engage the terminal of the lamp 9. The strip 25 engages the terminal of the lamp 11, while the strip 26 engages the terminal of the lamp 10. These contact strips are arranged as in my above referred to patent, and application. When the reflector 8 is inserted the terminal of the bulb 10 is passed through the opening 18 and engages the strip 26. This opening serves to readily center the reflector when it is inserted and the recess openings 21 and 22 of the ring 13 further serves to properly position the reflector in the casing or head member 4. The inner end of the reflector enters the opening 19.

For a full description of the circuits reference is made to the above referred to patent. When the ring 6 is threaded onto the threads 5 of the member 4 the contact strips 23, 24 and 26

and 25 are forced into the recesses 20, 21 and 22 and into contact with the ring of insulation 13. The reflector is therefore firmly held in place when in use.

5 From this description it will be seen that I have provided a simple and inexpensive construction for insulating the reflector from the metallic casing and for positioning the reflector in the lamps when inserted.

10 What I claim is:

1. As an article of manufacture for the purpose described, a flat ring of insulating material formed with a central opening and with oppositely disposed recesses extending 15 from the opening, a bar secured to the ring and formed with an opening which is located in the line which passes through the oppositely located recesses, whereby a reflector with a centrally disposed socket may be 20 accurately positioned in relation to the ring.

2. In combination in an electric lamp having a metallic cap piece, a metallic reflector located in the cap piece with electric bulb sockets attached thereto, a ring of insulating material engaging the cap piece, a bar diametrically secured to the ring and extending across the opening of the same, and formed with an axial opening for receiving a bulb socket on the reflector for positioning the reflector in the metallic cap piece, as described.

25 In witness whereof, I hereunto set my hand this 28th day of January, 1930.

JAMES L. SHANNON.
